V. O. SAMPSON

TRACK BRACE AND GAUGE

Filed Nov. 5, 1926

Fig. 3.

J. A. Wynn

WITNESS:

V. O. Sampson
INVENTOR
BY *Victor J. Evans*

ATTORNEY

UNITED STATES PATENT OFFICE.

VICTOR O. SAMPSON, OF WOODLAND, WASHINGTON.

TRACK BRACE AND GAUGE.

Application filed November 5, 1926. Serial No. 146,500.

My present invention has reference to that class of switch rods used to connect the switch rails together so that they move simultaneously in the shift of position, and my object is the provision of a device for this purpose which is of an adjustable nature so that the switch rails can be properly gauged.

A further object is the provision of a switch rod that comprises adjustably associated sections, the outer sections of which having laterally extending plates designed to be received in the fishing spaces of the switch rails and secured to said rails, and further wherein the throw bar for the switch rod forms a means for connecting the inner sections of the said rod but which throw bar is insulated from the said switch rod so as to not short circuit the electric current when the switch rails are employed as conductors.

To the attainment of the above broadly stated objects and many others which will present themselves as the nature of the invention is better understood, the improvement further resides in certain other novel features of construction, combination and operative association of parts, a satisfactory embodiment of which is disclosed by the accompanying drawings.

30 In the drawings:

Figure 1 is an elevation of the improvement, the switch rails being in section.

Figure 2 is a top plan view thereof.

Figure 3 is a detail sectional view on the line 3—3 of Figure 2.

The switch rails 1 have received in their inner fishing spaces and bolted to the webs thereof, plates 2. Each plate 2 is centrally formed with an inwardly directed shank 3, the said shanks having their outer portions round in cross section and the said outer portions are threaded, as at 4. The threaded portions of the shanks 3 have transverse openings 4' therethrough. These threaded shanks are engaged by the threaded bores of turn buckles 5. The turn buckles are provided with elongated aligning slots 6, and when the turn buckles are adjusted on the shanks 3 there are passed through these slots and through the openings 4' in the said shanks, holding pins 7. The opposite threads in the bore, at the inner ends of the

turn-buckles are engaged by similarly hand pitched threads on the cross sectionally rounded ends of members 8. The members 8 have their outer ends widened and flattened, as at 9. The threaded ends of the members 8 have transverse openings 10 therethrough to align with the elongated slots in the turn-buckles, and when the turn buckles are adjusted on the members 8 there are passed through the said slots and openings holding pins 11.

The straight and flattened ends 9 of the members 8 rest on a plate 13 of insulating material, and the plate 13 rests on the throw bar 14 for the switch points. Bolt members 15 engaged by nuts 16, hold the ends 9 of the members 8 connected to the plate 13 and to the throw bar 14. The bolts pass through insulator sleeves that are let in the bolt openings in the ends 9 of the members 8 and the members 13, and 14.

The simplicity of my construction and the advantages thereof will, it is thought, be perfectly apparent to those skilled in the art to which such invention relates when the foregoing description is read in connection with the accompanying drawings, it being, of course, understood that I do not wish to be limited to the precise details of construction herein set forth and hold myself entitled to make such changes therefrom as fairly fall within the scope of what I claim.

Having described the invention, I claim:

1. A combined gauge brace and connecting rod for switch points, comprising threaded members having plates on their outer ends which are received in the inner fishing spaces of switch rails, and are bolted to the webs thereof, a turn buckle screwed on each of the said threaded members, removable means locking the turn buckles on the members, flat members having rounded and threaded ends also engaged by the turn buckles, means for adjustably locking the turn buckles on said members and a throw bar underlying and connecting said last mentioned members.

2. A combined gauge, brace and connecting rod for switch points, comprising threaded members having plates on their outer ends which are received in the inner fishing spaces of switch rails, and are bolted

to the webs thereof, a turn buckle screwed on each of the said threaded members, removable means locking the turn buckles on the members, flat members having rounded and threaded ends also engaged by the turn buckles, means for adjustably locking the turn buckles on said members, a plate of in-

sulating material on which the flat ends of the last mentioned members rest, a throw bar underlying said plate and securing means ¹⁰ connecting the throw bar to the plate and to the ends of the said members.

In testimony whereof I affix my signature.
VICTOR O. SAMPSON.
